UNITED STATES PATENT OFFICE.

EDWIN B. STIMPSON, OF BROOKLYN, NEW YORK, ASSIGNOR TO EDWIN B. STIMPSON COMPANY, OF BROOKLYN, NEW YORK.

RIVETING MACHINE.

Application filed July 19, 1922. Serial No. 575,946.

To all whom it may concern:

Be it known that I, EDWIN B. STIMPSON, a citizen of the United States, residing at Brooklyn, in the county of Kings and State 5 of New York, have invented certain new and useful Improvements in Riveting Machines, of which the following is a specification.

This invention relates particularly to riveting machines of the type in which the rivets slide down an incline onto a guide beneath the driving plunger. Upon striking this guide there is a tendency for the rivets to rebound and get out of position.

15 The principal objects of the invention are to prevent this rebound and to overcome the so-called "tumbling" tendency of the rivets.

The novel features of construction and 20 combinations of parts which make possible the attainment of these objects are exemplified in the accompanying illustrations forming part of this specification.

Figure 1 is a broken front view of the 25 head portion of a riveting machine having the invention incorporated therein, with the front or near section of the rivet guide omitted to better disclose the relation of the parts.

30 Figure 2 is a horizontal sectional view on substantially the plane of line 2-2 of Figure 1.

Figure 3 is a detached perspective view of the rivet driving plunger.

35 The head portion of a riveting machine is indicated at 1 having the usual driving spindle 2 and rivet feeding mechanism at 3 terminating in an inclined chute or guide-way 4.

40 At the foot of the chute, beneath the plunger, is the guide for directing the rivets during the driving operation, which is shown as consisting of cooperating guide members or sections 5, 6 supported from the

45 slide 7 by the spring arms 8 and 9. These cooperating guide members are shown as removably and adjustably supported by means of the holding screw 10 and wing nut 11.

50 The rivet guide forms in effect a pocket at the foot of the guide chute to catch and hold the rivets in position to be acted upon by the plunger.

Overstanding the pocket provided by the 55 rivet guide is a hold-down device shown in

the form of a narrow finger projecting from the upper side of the guide chute on an incline down substantially over the center of the pocket and terminating at a point closely adjacent the head of a rivet seated 60 in the pocket. The extreme end of this guide finger is shown as faced off substantially horizontal so as to permit the rivet to slide squarely into position beneath the same. The driving plunger is shown as 65 constructed with a removable end section 13 having a reduced portion 14 fitting in a socket 15 in the body of the plunger and held in place by a set screw 16. This removable section is grooved in one side at 70 17 to pass over the projecting hold-down finger 12 and is shown as cupped at 18 to fit the head of the rivet.

A special feature of the invention is the utilization of the plunger to assist in holding the rivets under proper control. This is effected by releasing one of the rivets at each downward stroke of the plunger, so that the same will lie against the side of the plunger, in readiness to drop into the 75 pocket just so soon as the plunger is retracted. In a preferred operation of the machine, therefore, a feed slide 19 is operated to release the lower rivet when the plunger is down in position, blocking the 80 lower end of the inclined chute 4. The rivet then is ready to slide easily into position on the guides and beneath the end of the hold-down finger the instant the plunger frees the same. In this way the 85 extent of the drop is materially reduced and the rivet comes accurately to rest in the hollow or pocket at the top of the guides. Even with so short a drop, however, there 90 is a tendency for the rivets, particularly those with large heads and short shanks, to rebound and "tumble." This effect is overcome in its incipiency by the hold-down finger which immediately checks any rebound movement and returns the rivet to 95 its proper position on the guides. Thus without restricting the movement of the rivet or delaying the action in any way, the rebounding and tumbling tendencies are 100 effectually overcome.

105 What I claim is:

In a machine of the character disclosed, a rivet guide having a pocket to receive and support the head of a rivet, rivet feeding means including an inclined chute for 110

delivering the rivets to the pocket, a stationary hold-down finger forming the delivery end of one guide wall of the chute and having a projecting portion inclining downwardly to and terminating at a point substantially over the center of the head of a rivet supported in the pocket, and a

plunger for operating on the head of a rivet so supported, having a groove in one side to receive the projecting portion of the hold-down finger.

In testimony whereof I affix my signature.

EDWIN B. STIMPSON.
